UNITED STATES PATENT OFFICE.

FRANK E. ORMSBY, OF CHICAGO, ILLINOIS.

CALIPER OR INDICATING GAGE.

1,349,091.

Specification of Letters Patent. Patented Aug. 10, 1920.

Application filed December 6, 1918. Serial No. 265,591.

To all whom it may concern:

Be it known that I, FRANK E. ORMSBY, a citizen of the United States, residing at Chicago, in the county of Cook and State 5 of Illinois, have invented a new and useful Caliper or Indicating Gages, of which the following is a specification.

The object of my invention is to provide a new and improved combination of the 10 principles involved in calipers and indicating gages in a manner to simplify construction, enhance speed in its use and bring to practical accuracy its application and efficiency.

15 My invention consists of a caliper indicating gage, made from steel, designed for testing to workable fractions of an inch, borings, shafts, shells and all things to which such tools apply; also for height or 20 surface gaging, tests and the like.

The invention also consists in parts and combinations of the same fully described and set forth hereinafter.

Reference is to be had to the accompanying 25 drawings, forming a part of this specification, in which similar references to letters indicate corresponding parts in all the figures.

Figure 1 is an elevation of said tool, set 30 for inside application-testing borings and surfaces. Fig. 2 is an elevation showing the tool set for outside application - testing shafts, shells, and all outside measurements. Fig. 3 is an elevation of the reverse side of 35 the tool, showing the manner of spreading the legs and adjusting parts hereinafter described.

Attached to the bottom of the main portion of leg A, Fig. 1, is a needle-bar or 40 pointer *c*, projecting below the end of said leg A, forming contacting points, thence extending along the surface of said leg A to the graduated scale lines *h* under the main joint, showing by the throw of said needle-bar micrometric variations at the lower or 45 contacting surfaces.

Near the lower end of said needle-bar is a spring *f*, for regulating the needle for either inside or outside application. Said 50 spring *f*, Fig. 1, is securely fastened by means of a set screw to the frictional stud upon which the needle bar plays, and the other or upper end of said spring is bent to clasp the needle bar on either side, the 55 raising and shifting of the same changing

the registry for either inside or outside application.

Leg B is somewhat shorter than leg A, to which is frictionally joined a specially curved adjustable bar *e*, which forms an extension to leg B and which is adjustable for either inside or outside application, said bar being held firmly in position by a set screw *m* Fig. 3.

Fig. 1 shows the adjustment for inside 65 application, and Fig. 2 shows the curved bar *e* reversed and set for outside use.

The adjustment of the spread of the legs is accomplished by means of a simple rod C, Fig. 3, having a right thread running 70 from the center to one end, and a left thread running to the opposite end, said rod passing back and forth through two frictional stud nuts *i* attached to legs A and B respectively, with thumb screw *n* held in position by two lock nuts *o*; the advantage of this arrangement being in doubling speed in adjusting to sizes and maintaining perfect rigidity at all times, and in simple 75 construction and efficiency.

At the upper ends of legs A and B are indicating lines *h* showing the spread of the contacting points of said legs to the fraction of an inch, enabling the user to set the tool very closely to size, a slight turn to 85 bring the needle-bar *c* to the test point on scale *d* completing the operation.

I am aware that calipers and indicating gages are made in various forms, showing 90 jointed legs, indicating needles or pointers and attachments therefor, and that needles or pointers are in general use in various articles of manufacture; but I am not aware that a caliper indicating gage has been produced combining the essential features herein described in the simple form as shown; I therefore, do not claim such a combination broadly; but 95

What I do claim as my invention and desire to secure by Letters Patent, is—

1. In caliper indicating gages, two legs of different lengths, pivotally connected to each other and having scales at the pivotally connected ends thereof, each leg having a point member pivotally connected thereto at the free end thereof, one of said legs having a secondary scale and the point member pivotally connected thereto having an indicator extension adapted to move over said secondary scale. 100

110

2. In caliper indicating gages, two legs of different lengths pivotally connected to each other and having scales at the pivotally connected ends thereof, each leg having a point member pivotally connected thereto at the free end thereof, one of said legs having a secondary scale, the point member pivotally connected thereto having an indicator extension adapted to move over said secondary scale, and a spring secured at one end to said extension and having its other end adapted to engage either edge of the leg on which said extension is mounted.
3. In caliper indicating gages, two legs of different lengths pivotally connected to each other and having scales at the pivotally connected ends thereof, each leg having a point member pivotally connected thereto at the free end thereof, one of said legs having a secondary scale, the point member pivotally connected thereto having an indicator extension adapted to move over said secondary scale, a spring secured at one end to said extension and having its other end adapted to engage either edge of the leg on which said extension is mounted and a set screw passing through the other of said legs and adapted to secure the point member

ber pivotally connected thereto in fixed position thereon.

4. In caliper indicating gages, two legs of different lengths pivotally connected to each other and having scales at the pivotally connected ends thereof, each leg having a point member pivotally connected thereto at the free end thereof, one of said legs having a secondary scale, the point member pivotally connected thereto having an indicator extension adapted to move over said secondary scale, a spring secured at one end to said extension and having its other end adapted to engage either edge of the leg on which said extension is mounted, a set screw passing through the other of said legs and adapted to secure the point member pivotally connected thereto in fixed position thereon, each leg having screw threaded studs pivotally connected thereto, and a screw having right and left-hand threads engaging said studs to adjust the legs to and from each other.

FRANK E. ORMSBY.
